US00D888355S

(12) **United States Design Patent** (10) **Patent No.:** **US D888,355 S**
(45) **Date of Patent:** **** Jun. 23, 2020**

(54) **LAUNDRY WASHING MODULE**

(71) Applicant: **WHIRLPOOL CORPORATION**,
Benton Harbor, MI (US)

(72) Inventors: **James Kendall**, Mt. Prospect, IL (US);
Ameresh Viswanathan, Saint Joseph,
MI (US)

(73) Assignee: **Whirlpool Corporation**, Benton
Harbor, MI (US)

(**) Term: **15 Years**

(21) Appl. No.: **29/638,235**

(22) Filed: **Feb. 26, 2018**

Related U.S. Application Data

(63) Continuation of application No. 29/582,125, filed on Oct. 25, 2016, and a continuation of application No. 29/582,129, filed on Oct. 25, 2016, and a continuation of application No. 29/582,131, filed on Oct. 25, 2016, said application No. 29/582,125 is a continuation of application No. 12/489,710, filed on Jun. 23, 2009, now abandoned, said application No. 29/582,129 is a continuation of application No. 12/489,710, filed on Jun. 23, 2009, now abandoned, said application No. 29/582,131 is a continuation of application No. 12/489,710, filed on Jun. 23, 2009, now abandoned, which is a continuation of application No. 11/322,740, filed on Dec. 30, 2005, now abandoned, and a continuation of application No. 11/323,125, filed on Dec. 30, 2005, now Pat. No. 7,628,043, and a continuation of application No. 11/323,221, filed on Dec. 30, 2005, now Pat. No. 7,624,600.

(57) **CLAIM**

The ornamental design for a laundry washing module, as shown and described.

DESCRIPTION

FIG. 1 is a front perspective view of a laundry washing module showing our new design; and, FIG. 2 is a front perspective view of the laundry washing module of FIG. 1, with a wash drawer of the laundry washing module in an opened position. The broken lines show portions of laundry washing module that form no part of the claimed design.
